UNITED STATES PATENT OFFICE.

CLAUDE A. BULKELEY, OF WILMINGTON, DELAWARE, ASSIGNOR TO E. I. DU PONT DE NEMOURS & COMPANY, OF WILMINGTON, DELAWARE, A CORPORATION OF DELAWARE.

APPARATUS FOR THE PRODUCTION OF POWDERED MATERIAL.

Application filed December 9, 1919, Serial No. 343,467. Renewed November 22, 1923.

To all whom it may concern:

Be it known that I, CLAUDE A. BULKELEY, a citizen of the United States, and a resident of Wilmington, in the county of New Castle and State of Delaware, have invented a certain new and useful Apparatus for the Production of Powdered Material, of which the following is a specification.

This invention relates to apparatus for the production of finely powdered material, and since the illustrated apparatus finds particular application in the art of producing bronze powder, although it is not restricted thereto, I describe it with more particular reference to that art.

In the making of bronze powder by hammering the metal to reduce it to small particles it is important that the finished fine powder be accurately separated from the unfinished larger particles, otherwise the powder will have its quality impaired by the presence of particles too large to be properly included therein. Also, it is important that when any particles have been reduced to desired size they be removed from the action of the reducing machine, otherwise such particles become over-treated, thereby becoming granular and losing their brilliancy, instead of remaining flat, flake-like and brilliant.

Various apparatus have heretofore been proposed for the grinding and separation of certain materials but such apparatus are not well adapted to the production of bronze powder, for they do not separate the particles with sufficient accuracy, and have not suitable provisions for avoiding over-treatment. For example, it has been proposed to assemble together a grinding machine discharging into a hopper below the machine, a separator having a screen arranged therein as an operative part thereof, a pipe for conducting back to the grinder material that does not pass the screen, and piping combined with a fan for carrying the ground material from the hopper to the separator and screen. In such apparatus there is not a sufficiently accurate separation of the materials at the grinding machine and therefore not only does much material leave the machine after it should and so is over-treated, but also much material leaves before it should and so has to be rehandled and returned to the machine. Another difficulty is that since the screen

is in the separator and an operative part thereof, it is subjected to forces tending to forcibly drive the particles through the screen, e. g., forces causing the separation, whereby the accuracy of the screening is destroyed, resulting in the presence in the supposedly "fine" powder of a large number of coarse particles driven through the screen. Moreover, the screen of the apparatus, being stationary, has not that high degree of ability to screen the powdered material accurately which it is desirable to have present in a screening device used for screening bronze powder. I have devised an apparatus by the use of which bronze powder of desired fineness and uniformity, and having its particles flat, flake-like and brilliant, can be conveniently produced.

An object of my invention is to provide an apparatus for the production of powdered material which apparatus shall provide for the removal of the material from the reducing machine upon the material reaching the desired degree of fineness, thereby avoiding over-treatment, and also provide for the accurate separation of the finished material from the unfinished.

To this end, and also to improve generally upon apparatus of the character indicated, my invention consists in the matters hereinafter described and claimed.

In the accompanying drawings:—

Figure 1 is a somewhat diagrammatic and conventional elevational view of an apparatus embodying my invention;

Figure 2 is a sectional view of the reducing machine included in the apparatus illustrated in Figure 1;

Figure 3 is substantially a longitudinal sectional view of the rotary screen and adjacent parts, included in the apparatus illustrated in Figure 1, and

Figure 4 is a cross-sectional view substantially on the line 4—4 of Figure 3, but with the partition wall of the casing omitted.

Referring now to the drawings, the illustrated apparatus comprises a reducing machine 1, in the character of a stamping mill, a cyclone separator 2, a rotary, horizontal, polygonal screen 3, and a fan or blower 4. An air tight system of pipes 5, 6 and 7 provides for circulation of air from the mill 1, through the fan 4, to the separator 2, and back to the mill. A pipe 8 is provided for conducting to the rotary screen 110

3 the powder removed from the air current by the separator 2; a pipe 9 serves to conduct away the finished material passed through the meshes of the screen; a pipe 5 10 returns unfinished material from the discharge end of the screen to the machine, and the pipe 11, connected with the pipe 10, returns to the machine such material as may by chance fail to enter, or to 10 remain in, the entrance end of the screen. The machine, fan and screen are driven from any suitable source or sources of power (not shown), the drives being independently controllable, as by changing the pulley sizes, so that the desired speed of operation may be selected for each, independently of the others.

In the operation of the apparatus, coarse bronze powder is supplied at intervals to 20 the hopper 12 on an extension 10^a of the pipe 10 and is reduced by series of hammers as 13 and 14. The particles as they become sufficiently reduced, are carried up the pipe 5 by the air current, separated from 25 the air by the separator, and discharged into the screen; the air returning from the separator to the machine through the pipe 7. Finished powder is discharged from the screen through the pipe 9, unfinished material is discharged through the pipe 10 back to the machine, and "spilled" material is discharged through the pipes 11 and 10 back to the machine. Thus the action is 30 continuous, coarse material being supplied as required to the hopper 12 and finished material removed at the lower end of the pipe 9.

As shown more particularly in Figure 2, the pipes 5 and 7 communicate with the 40 reducing chamber 15 of the machine 1 above the anvils 16, 16, whereby the material being reduced is not directly discharged into the pipe 5, that is, is not discharged by gravity, for example, and the air entering 45 at the pipe 7 does not blow up through the charge C, but, instead, blows over it. With this arrangement, with the hammers, as 13 and 14, keeping the charge in a constant state of agitation the smaller particles float in the air current. The strength 50 of the air current is so regulated that these finer lighter particles are carried upward to the screen, while the coarser heavier particles are left behind for further treatment, and an initial separation of the particles is made. The finer particles are removed from the machine as soon as they are sufficiently reduced and therefore are not subjected to over-treatment that would 55 tend to render them granular instead of flat, flake-like and brilliant. For practical reasons, I prefer not to attempt to make the separation at the reducing machine absolutely exact, but, rather, use an air current sufficiently strong to carry away 60

a certain amount of slightly oversize particles, and I make the final separation at the screen 3.

As previously pointed out the screen is 70 separate and distinct from the cyclone separator 2. With the screen thus separate and distinct from the separator, there is no forcible driving of oversize particles through the screen—an action that would 75 of course introduce inaccuracies into the screening. Also, by having the screen separate from the separator I am able to use as fine and delicate a screen as I desire, not having to consider what might be the effect on such a screen were it to be placed 80 in the separator to be subjected to swirling particles and so forth. Again, by having the screen separate from the separator I am enabled to use a rotary screen, which I could not feasibly do were the screen within 85 the separator; and so can get a more accurate separation than would be conveniently possible with a stationary screen.

It will be noted also that, since the air current is created, not by the action of the reducing machine, but by an independent element, the fan, the strength of the current can be regulated as desired, without regard to what the desired speed of 90 the machine may be. Also, the effect of 95 the screen is determinable by its speed of rotation and so forth and is not dependent upon the strength of the air current or forces acting within the separator, and, so, can be regulated to exactly meet desired 100 conditions; and the air current can be regulated without having to consider its effect at the screen. Thus the effect of each element of the apparatus can be accurately 105 regulated, independently of the others, to secure the best results.

The details of the various elements of the apparatus may be of any suitable or preferred character. As here illustrated the reducing machine is of the type commonly 110 called a "sixteener machine" its series of hammers, as 13, being driven by cams, as 17, carried by a shaft 18; and its series of hammers, as 14, being driven by cams, as 19, carried by a shaft 20. One shaft, 115 as 18, is driven by the belt pulley 21, and the motion is transmitted by gearing 22^a, 22^b to the shaft 20. The fan is of the usual type driven by the belt pulley 23 from, say, an electric motor (not shown). 120 The separator, as previously mentioned, is of cyclone type, the air entering at 24, being centrifugally freed from the particles by the action within the separator, and leaving at 25. The screen 3 comprises a 125 frame composed of the elements 26 which are carried by the spider 27 and the end plate 28 mounted to rotate with the shaft 29 driven by the pulley 30. On the elements 26 is preferably carried 200 mesh, 130

silk bolting cloth. The receiving end of the screen is open, while the end plate 28 closes the discharge end except for exit apertures 31. Desirably the pipe 5 is, 5 as shown, of relatively large diameter adjacent the machine 1 and of relatively small diameter along the major portion of its length. Desirably, too, the lower portion of the pipe 7 is of smaller diameter than the 10 portion thereof adjacent the separator. Conveniently a portion 7^a of the pipe 7 may be flexible, as of canvas, to facilitate the opening of the door 1^a of the machine, for inspection or any desired purpose. It 15 will be understood that proper brackets, supports, and so forth, for the various elements of the apparatus are provided, but to avoid confusion no attempt is made to illustrate such parts. Also, although for 20 simplicity in the drawings but one entrance pipe 7 and one exit pipe 5, and but one separator, one screen, etc., have been shown, it will be understood that as many entrance and exit pipes spaced along the chamber 15, 25 and as many separators, screens, etc., can be used as are desirable for the objects sought.

Although I have described my invention with more particular reference to the illustrated embodiment, it will be understood 30 that I do not restrict it thereto, for it may be embodied in many other and different apparatus.

Having thus described my invention, I 35 claim:—

1. In an apparatus for the production of powder, in combination, a reducing machine having a chamber for holding the material to be acted on, and means in said chamber 40 for acting on the material, conductors providing an air circuit with said chamber included therein, means for moving air through said circuit, a separator included in said circuit, and a screen located without 45 said circuit and operatively distinct from the separator, said separator and screen being arranged for the discharge of material from the separator to the screen.

2. In an apparatus for the production of 50 powder, in combination, a reducing machine having a chamber for holding the material to be acted on, and located to support such material upon the bottom thereof, and means in said chamber for acting on the material, 55 conductors providing an air circuit with said chamber included therein, with the entrance conductor and the exit conductor communicating therewith above the bottom thereof, thereby to provide that the air cir- 60 culating through said chamber shall pass across the material, means for moving air through said circuit, a separator included in said circuit, and a screen, said separator and screen being arranged for the discharge 65 of material from the separator to the screen.

3. In an apparatus for the production of powder in combination, a reducing machine having a chamber for holding the material to be acted on, and located to support such material upon the bottom thereof, and means 70 in said chamber for acting on the material, conductors providing an air circuit with said chamber included therein, with the entrance conductor and the exit conductor communicating therewith above the bottom 75 thereof, thereby to provide that the air circulating through said chamber shall pass across the material, means for moving air through said circuit, a separator included in said circuit, and a screen located without 80 said circuit and operatively distinct from the separator, said separator and screen being arranged for the discharge of material from the separator to the screen.

4. In an apparatus for the production of 85 powder, in combination, a reducing machine having a chamber for holding the material to be acted on, and located to support such material upon the bottom thereof, and means 90 in said chamber for acting on the material, conductors providing an air circuit with said chamber included therein, with the entrance conductor and the exit conductor communicating therewith above the bottom 95 thereof, thereby to provide that the air circulating through said chamber shall pass across the material, means for moving air through said circuit, a separator included in said circuit, and a screen located without 100 said circuit and operatively distinct from the separator, said separator, screen and machine being arranged for the discharge of material from the separator to the screen and from the screen to the machine.

5. In an apparatus for the production of 105 flat-flake powder, in combination, a stamping mill having a stamp-and-anvil chamber and a stamp in said chamber for stamping and agitating the material, conductors providing an air circuit with said chamber included therein, with the entrance conductor and the exit conductor to and from said chamber communicating therewith above the bottom thereof, means for moving air through said circuit, a separator included in 110 said circuit, and a screen, said screen being operatively distinct from said separator, said separator and screen being arranged for the discharge of material from one to the other.

6. In an apparatus for the production of 115 flat-flake powder, in combination, a driven stamping mill embodying a chamber for material, said chamber having anvil means at its bottom, said mill also embodying stamping means operative in said chamber and cooperating with said anvil means to reduce the material, conductors providing an air circuit with said chamber included therein 125 with the entrance conductor and the exit 130

conductor to and from said chamber communicating therewith above said anvil means with said stamping means substantially in the line of the air current, driven 5 means for moving air through said circuit, a separator included in said circuit, a screen, a conductor from said separator to said screen, a conductor from said screen to said mill for returning unfinished powder there- 10 to, a conductor for discharging finished powder from the screen, and means for driving said mill and said moving means.

7. In an apparatus for the production of powder, in combination, a driven stamping 15 mill embodying a chamber for material, said chamber having anvil means at its bottom, said mill also embodying stamping means operative in said chamber and co- operative with said anvil means to reduce

the material, conductors providing an air 20 circuit with said chamber included therein with the entrance conductor and the exit conductor to and from said chamber communicating therewith above said anvil means with said stamping means substantially in 25 the line of the air current, driven means for moving air through said circuit, a separator included in said circuit, a driven rotary screen, a conductor from said separator to said screen, a conductor from said screen 30 to said mill for returning unfinished powder thereto, a conductor for discharging finished powder from the screen, and means whereby said driven mill, moving means, and screen can be driven each at a speed in- 35 dependent of that of the others.

In testimony whereof I affix my signature.
CLAUDE A. BULKELEY.
